[57] CLAIM

The ornamental design for a motorcycle handlebar, as shown and described.

DESCRIPTION

FIG. 1 is a top plan view of motorcycle handlebars showing my new design. Elements which support motorcycle handlebar according to the present invention with respect to a motorcycle, but do not form a part of the present invention, are illustrated with broken lines;

FIG. 2 is a bottom view of the motorcycle handlebar shown in FIG. 1;

FIG. 3 is a side elevational view of the motorcycle handlebar shown in FIG. 1;

FIG. 4 is a back elevational view of the motorcycle handlebar shown in FIG. 1;

FIG. 5 is a front elevational view of the motorcycle handlebar shown in FIG. 1; and,

FIG. 6 is a cross-section view taken of the motorcycle handlebar along line 6—6 in FIG. 1.
